PARACHUTE

Frank E. Monks, Pittsburgh, Pa., assignor to Full-
er Label & Box Company, Pittsburgh, Pa., a
corporation of Pennsylvania

Application November 15, 1943, Serial No. 510,347

5 Claims. (Cl. 244—142)

This invention relates to parachutes and more particularly to a chute peculiarly suitable for use in aerial delivery of goods packed in a container. The instant application is a continuation in part of my application Serial No. 502,165, filed September 13, 1943.

A prime desideratum of this invention is to facilitate safe aerial delivery of goods from an aircraft at very low altitudes and to enable substantially effortless launching of a chute-supported container in a minimum of time without distracting the pilot's attention from handling the craft.

An important feature in insuring successful delivery from low altitudes resides in so constructing and folding a chute that it may be easily associated with a receptacle or container as a mandrel or core and secured thereto in such manner that the two separate substantially instantaneously when the securing means is released.

Another important feature in obtaining this end resides in arranging the chute folds so that on separation of a chute and container the chute will blossom substantially instantaneously.

Among other objects of the invention are to provide a chute which is easily and quickly made from any of numerous materials of which there is always an abundance, to simplify the chute design and construction so that it can be provided at extremely low cost with the use of unskilled labor, and to arrange the folds so that, in addition to accomplishing the hitherto described primary objective, the chute may be readily and quickly assembled about the container in a minimum of time by one unskilled in the usual machinations involved in such procedure.

Among other objects of the invention is to so design the chute that when open it provides a substantial supporting area in proportion to a maximum probable load in the container, thus insuring safety in completing the intended operation.

Various other objects and meritorious features of the invention will become apparent from the following description taken in conjunction with the drawings, wherein like numerals refer to like parts throughout the several figures, and wherein:

Figure 1 is a perspective of the chute folded about a container;

Fig. 2 is a top plan view;

Fig. 3 is a view similar to Fig. 2 illustrating the chute as it begins to open;

Fig. 4 is a perspective of the chute during an early stage of its blossoming action;

Fig. 5 is a fragmentary elevation illustrating 55

the relative position of chute and receptacle as the two begin to separate;

Fig. 6 is an elevation of the chute after blossoming fully;

Fig. 7 is a section along 7—7 of Fig. 6;

Fig. 8 is a section along 8—8 of Fig. 6;

Fig. 9 is an elevation of a somewhat modified form of chute;

Fig. 10 is a section along 10—10 of Fig. 9;

Fig. 11 is a section along 11—11 of Fig. 9;

Fig. 12 is a section along 12—12 of Fig. 9;

Fig. 13 is a fragmentary perspective of a somewhat modified form of chute, and

Fig. 14 is a fragmentary perspective of still another modified form of chute.

While the particular form of container is in no wise important to the instant invention, a description of the manner in which it is associated with my improved chute is rather essential to a full understanding of the operation of the chute and the various advantages attributable to and inherent therein. For that reason the receptacle has been illustrated in Figs. 1, 2 and 5 and the numeral 10 broadly designates the same. For purposes of illustration a tubular receptacle has been shown.

A centrally apertured plaited parachute is folded or furled about the container in such manner that when the plaits begin to unfold their engagement with the receptacle is immediately freed and all friction between the two as the receptacle drops from within the folds is eliminated. The parachute has been indicated broadly by the numeral 16 and its particular construction and manner of plaiting and folding are of distinct importance in obtaining substantially instantaneous separation of the chute and the receptacle after the folds of the former are released, and substantially instantaneous blossoming of the chute immediately thereafter.

Referring momentarily to Fig. 6 of the drawings will facilitate a clear understanding of the nature of the fold lines delineating the plaits 18, which will be more specifically alluded to hereafter. In the unfolded or operative position illustrated therein it is apparent that there are successive pairs of reversely folded lines 19 and 21 which, when folded, form the accordion or umbrella plaits designated by the numeral 18. Alternate fold lines 19, 21 are reversely folded when packing the chute, the material folding inwardly about lines 19 and outwardly about lines 21. Furthermore, it is important to note that the outer marginal ends of each fold line 19 on one side of a fold line 21 is more closely spaced from

the latter than the fold line 19 on the other side thereof, and that each more closely spaced pair of fold lines 19, 21 nearly intersects at the margin of the central aperture whereas the next adjacent pairs do not. Thus the peripheral distance between each alternate or second pair of converging fold lines 19, 21 is less than the peripheral distance between each intervening pair of converging fold lines.

In the form illustrated the angle between each successive pair of fold lines 19, 21 is substantially the same and to this is attributable the uniformity of the exposed portions of plait 18 when the chute is in folded or static form, as illustrated in Figs. 1, 2 and 5. The outer marginal spacing of successive pairs of fold lines and the angles between them should be so proportioned and related to one another that the chute will fold into substantially tubular form. The invention is not, of course, limited to the exact relationship of spacing and angle illustrated and described, but the specific arrangement obtains extreme accuracy of tubular form and a geometric symmetry of fold lines and exposed plait walls which is very desirable.

Insofar as this phase of the invention is concerned, it should be noted that alternate fold lines 19 are so angulated and spaced with reference to the fold lines 21 that when the material is folded and flattened along the fold lines to form plait 18 the fold lines 21 extend substantially parallel to one another, as may be most clearly seen from Figs. 2-4. When in static condition, an open ended, thin walled, substantially tubular form of pack is thus obtained. A tubular pack of this sort is readily conformed to any elongated design of container, whether tubular or not.

The parachute when in static condition, folded about the receptacle as a core with the upper end of the receptacle extending through or aligned with the central aperture of the chute, may perhaps best be described as constituting a series of umbrella plait 18, said plait being truncated or cut off somewhat short of the point where each pair of the more closely spaced adjacent converging fold lines 19 and 21 would normally meet to thus provide at 20 a fold capable of lying snugly against the wall of the receptacle but adapted immediately on release of pressure retaining the same in that position to expand radially outwardly. Such expansion immediately on release of restraining pressure permits the receptacle to drop freely through the folded chute even during the period of unfolding and materially facilitates instantaneous freeing of the receptacle from the chute immediately on release of such restraining pressure.

Shroud lines 22 are secured in any desired manner at spaced points around the top of the receptacle and fastened at their free extremities to spaced points about the parachute periphery, preferably at fold lines 19. The plait of the chute are held in folded position about the receptacle by some suitable means such as frangible rings or tapes 28, which latter serve likewise to position a static cord 32 having a free extremity 30 adapted to be grasped by the person launching the mechanism. Any suitable mechanism such as a section of corrugated fiberboard or sheet 34 may be used to position the loops of static cord 32, the extremity of which opposite the extremity 30 is connected in some suitable manner to the rings 28 so that the latter will be

ruptured when the static cord is placed under tension, thus freeing the folds of the chute.

Means are provided to assure separation of the receptacle from the chute in the proper direction during the launching operation. In the embodiment illustrated a tape 38 is passed over the top of the receptacle, the ends being extended down over the wall thereof and secured in suitable fashion to the chute, as by adhering to the upper margin of a plait of the folded chute as indicated at 40.

In launching, after the static line has unreeled fully the weight of the falling device causes the retaining rings 28 to rupture. Freed of restraint, the plait move outwardly from the receptacle against which they were held and air entering between the walls thereof causes the speed of the chute's descent to slacken as it unfolds. As the chute speed decelerates the container falls downwardly at a relatively constant speed. The rapidity with which my improved chute blossoms to fully expanded position is such that the shroud lines do not become taut against the container load until the chute has reached fully expanded position, or substantially so. Thus the device is provided no opportunity to gain any substantial momentum through gravity acceleration of the loaded container and may be launched from extremely low altitudes without fear of mishap. Low-altitude launching materially facilitates accuracy in locating the ground target and this is a very important factor in successful delivery of the loaded container.

With particular reference to Figs. 2, 3 and 4, it will be seen that, after the frangible means or retainer rings 28 have been ruptured to release the folds of the plaited chute, the plait immediately spring outwardly from the packed formation indicated in Figs. 1 and 2 to the position illustrated in Figs. 3 and 4. Not only do the plait spring or unfurl radially outwardly, but during this movement the walls of each plait tend to separate at their base as clearly indicated at 42. Substantially simultaneously the small folds 20 at the truncated top of each plait straighten out to some extent, aided in this movement not only by the unfurling of the lower portions of the plait but by the air which immediately begins to pass upwardly between the folds of the partially opened plait, to thereby expand the diameter of the central opening in the chute.

This action releases all friction between the receptacle core and the chute, permitting the air passing up at 42 between the plait walls to decrease the speed of the chute's descent and permit the container or receptacle to move downwardly from within the partially opened plait. During such relative movement of the receptacle and chute the latter blossoms forth as more air passes upwardly through 42, and blossoming action is complete or substantially so before relative descent of the receptacle has reached the limit permitted by shroud lines 22.

In Fig. 5 I have illustrated the relative positions of chute and receptacle when relative movement between the two begins immediately on rupture of the frangible retainer rings 28. The importance of strip 38 is apparent, since it renders impossible relative movement between these two elements other than in the proper direction, i.e., movement of the receptacle away from the top of the chute.

The material is of importance only insofar as controlled by practical considerations. The chute may be made from paper, fabric, plastic or any

combination thereof. If paper is used it may be either plane-surfaced or creped in one or both directions. Such creping tends to absorb any shock of opening. The material used may be coated or impregnated for fungicide and water resistance, or treated in any manner that circumstances may render desirable.

While the particular form of plait has been, it is believed, accurately described by general reference to an umbrella plait, it will be noted from Fig. 6 that such plait is formed by a pair of adjacent fold lines converging from spaced points around the margin of the chute periphery, such folds being in opposite directions. The difference in peripheral distances between adjacent pairs of converging fold lines 19, 21 represents the extent to which each plait is exposed, or not overlaid, by an adjacent plait when the chute is in folded or furled position. The outer radial margins of each plait in the form illustrated, it will be noted, are parallel. As heretofore explained, the plaits are truncated or sliced off at a point somewhat short of the normal meeting point of the more closely spaced converging plait fold lines, thereby assuring expansion of the central aperture of the parachute when the folded chute begins to open.

While, as hitherto explained, the chute may be made of any suitable material, it is perhaps preferable that there be a certain amount of rigidity or stiffness inherent in the material. Such property or characteristic tends to retain the chute plaits in position during successive stages of opening, and the resiliency in each such plait when folded or furled speeds the opening sequence, particularly at that stage immediately following rupture of the frangible means. Tough paper has been found eminently suitable.

All details of chute construction have been described in conjunction with the particular form illustrated. Nevertheless it should be fully understood that satisfactory operation may be obtained with an inverted arrangement wherein the folds or plaits 18 are positioned on the inside or, in other words, adjacent the container about which the chute is folded. Where pliable material as distinguished from material possessed of a certain amount of inherent rigidity, such as paper, is used, the action of a chute so folded is substantially the same as where the folds are on the outside, as in the embodiment shown in detail herein.

Where, however, processed fabric or paper constitutes the material of which the chute is fabricated, the unfurling action of an inversely folded chute immediately after release of the retaining tapes or rings 28 will be slightly different. Under these circumstances the flexibility or spring inherent in the folded plaits will cause the latter to move inwardly against the wall of the container. At the same time the walls of each plait will spread somewhat, as hitherto explained, and the small folds 20 will expand the opening forming the central aperture of the chute, thus permitting the container to slide downwardly with reference to the chute. Unfurling may not be quite so rapid where the plaits are adjacent the container wall, but the folds will spread against the resistance of the wall and permit air to move upwardly between the plait walls, thereby causing the chute to blossom in precisely the same manner as has hitherto been described.

Completion of the blossoming action may not be quite so rapid with the modified form, but the

speed of opening is quite sufficient for many purposes.

Reinforcing strips 44 are associated in some suitable manner along a portion of that part of each plait fold line exposed to view when the chute is folded. A reinforcing strip 46 is likewise secured around and to the outer margin of the chute. These strips may be separately secured or combined prior to securing to the chute.

10 Regardless of the manner in which the reinforcing strips are associated with the chute, a free tab 48 is so associated with either strip 44 or strip 46 as to extend beyond the margin of the periphery and to each of these one of the shroud lines 22 is secured in some suitable fashion.

In the embodiment illustrated in Fig. 6 the reinforcing strip 44 is stitched as indicated at 50 along the fold line when the plait is in folded position, and assumes substantially the form illustrated in Fig. 7 when the fold line is flattened. Marginal reinforcing strip 46 may be lapped over the margin of the chute and stitched thereto as indicated at 52. The reinforcing strips may be of any suitable material, fabric tape having been found eminently satisfactory even where the chute material is paper. Reinforcing strip 47 may be stitched in similar fashion around the margin of the central aperture of the chute.

In Figs. 9-12 a somewhat different manner of securing reinforcing strips as hitherto described has been illustrated. A marginal strip 54 is stitched to the margin of the chute. Prior to associating strip 54 with the chute a series of strips or shroud tapes comprising outer and inner reinforcing sections 56 and 58, respectively, are stitched to strip 54. These strips are secured to marginal strip 54 in such manner that a loop 60 extends beyond the margin of the strip. To these loops shroud lines 22 may be secured.

40 Adhesive is applied to the inner faces of sections 56 and 58 before stitching so that after the marginal strip 54 is stitched to the base of the chute these sections may be flattened against opposite sides of the chute material and readily adhered thereto. Preferably some type of thermoplastic adhesive is used and very strong adhesion may be obtained by passing a hot iron over sections 56 and 58, which may be regarded as shroud line tapes which also function to reinforce the chute or canopy itself.

A reinforcing strip or collar 62 may be adhered to the margin of the central aperture of the chute in the same manner as hitherto described in conjunction with shroud tapes 56 and 58. Furthermore, it has been found feasible, and in some ways more satisfactory, to adhere marginal reinforcing tape 54 around the base of the chute in the manner hitherto described in lieu of the stitching above suggested.

60 When using relatively stiff materials having inherent in them a certain amount of rigidity, such as paper or fabric reinforced paper, the material may not be sufficiently flexible to billow out into hemispherical shape when fully expanded. While such shape is not essential, more satisfactory descent is obtained thereby under some conditions.

In Figs. 13 and 14 I have illustrated an arrangement whereby substantial hemispherical shape is obtained with the use of material which might if uncontrolled offer a certain amount of resistance to the assumption of such shape. In Fig. 13 each fold 18 exposed when the chute is folded is secured to the underlying fold by a curved line of stitching 64 extending from an intermediate point

on the exposed fold line and intersecting the bottom edge of the plait walls at a point spaced from the fold line. In this construction it has been found very satisfactory to punch a hole 66 through the outer edges of the stitched folds and secure a shroud line 22 therein.

Fig. 14 represents a somewhat modified form of this concept wherein shroud tapes 68 are lapped over the fold lines and stitched to the superimposed folds along a straight diagonal line 70 extending from the fold line at an intermediate point thereon and intersecting the bottom edge of the plait walls at a point spaced inwardly from the fold line. A loop 72 may be formed at the bottom of each tape to which a shroud line 22 is secured.

While certain embodiments of my invention have been described herein for illustrative purposes, various modifications lying within the scope of the broad inventive concept will be apparent to those skilled in the art and for that reason I wish to limit myself only within the scope of the appended claims.

What I claim is:

1. A centrally apertured parachute embodying 25

alternate reverse fold lines angulated with reference to one another and converging from the outer periphery of the chute toward the margin of the central aperture, one set of alternate fold lines being angulated and spaced with reference to the other so that when the folds are flattened to form a series of plaits the fold lines of one of said alternate sets are substantially parallel to one another.

10 2. The arrangement set forth in claim 1 wherein the fold lines are truncated short of the normal meeting point of the more closely spaced converging fold lines.

3. The arrangement set forth in claim 1 wherein the parachute material possesses a limited amount of inherent rigidity.

4. The arrangement set forth in claim 1 wherein the parachute material is paper.

5. The arrangement set forth in claim 1 wherein reinforcing strips are associated with the chute along alternate fold lines, and shroud lines are secured to the outer extremities of said reinforcing strips.

FRANK E. MONKS.
